SECTIONAL SOLE AND CONNECTING MEANS
THEREFOR

Henry Ghez and Oscar Ghez, New York, N. Y.

Application June 2, 1942, Serial No. 445,435

2 Claims. (Cl. 36—33)

This invention relates to soles for footwear which are made of normally stiff or inflexible material and cut transversely into two or more sections interconnected by means of one or more strips of flexible material which is preferably resilient.

The main object of our invention is to utilize available cheap materials for shoe soles which will have certain of the advantages of rubber and leather, while allowing for economical use of 10 these two valuable materials.

Another object is to make soles of the character indicated having various forms of connecting means.

A further object is to have connecting means in such soles which serve as hinges and are anchored to the sole sections in secure manner.

Other objects and the various advantages of our invention will appear more fully as this specification proceeds.

In order to disclose in a clear manner the salient features of our invention, several forms thereof are illustrated by way of non-limiting examples in the accompanying drawing, in which,

Fig. 1 is a plan view of such a sole as seen from above and divided into two sections and provided with connecting means retaining the sections in assembled relation.

Fig. 2 is another plan view showing a sole divided into three sections which are connected together according to the principles of the invention.

Fig. 3 is a side elevation of the sole of Figure 1, partly in section to disclose detail.

Fig. 4 is a partial perspective of a modification.

Fig. 5 is a fragmentary side elevation showing another modification.

Fig. 6 is another fragmentary side elevation showing a further modification.

Fig. 7 is likewise a fragmentary side elevation illustrating still another modification utilizing two connecting means spaced above one another.

Fig. 8 is still another modification shown partly in section of the form of the connecting means shown in Figures 1 and 3.

Fig. 9 is also a modification showing how a group of arcuate springs may be used to interconnect the sole sections.

Throughout the view the same references indicate the same or like parts.

In order to economize in the use of leather, rubber and other valuable materials, which are greatly in demand, it is possible to use for the 55

soles of footwear several materials of inherently rigid or inflexible nature by subdividing a sole made of such material into sections and then connecting the sections by resilient or at least flexible connecting means. The sole itself can well be made of wood, metal, such as aluminum, hard plastic and any other available material which can be handled, while the connecting means are preferably of rubber, leather, flexible plastic, spring steel, beryllium copper in sheets, etc.

Thus, in the practice of our invention and referring again more particularly to the drawing, Figure 1 shows a sole generally indicated at 1 divided into sections 2 and 3 having a gap indicated at 4 between them, while the gap is bridged by a connecting member 5 which extends a distance into each of the sole members 2 and 3 forwardly and rearwardly in slots 6 and 7, while 20 rivets, nails or screws 8, 9 extend from the top toward the bottom or vice versa in the sole members through the end of the connecting means 5. Said connecting means is preferably of flexible and/or elastic plastic material, such as of the 25 vinyl series, or of leather, or even rubber, and it is of course possible to cement the same into the slots which have been cut to receive them in the sole member but cementing, riveting, nailing, etc., is optional. It is evident that a sole thus made 30 and secured to an upper for a shoe, a boot, or sandal would allow flexing of the foot when worn by virtue of the connecting means which allows the forward section 3 to bend upwardly with respect to sole member 2, while retaining the forward section 3 assembled with the rear section 2. As shown in Figure 2 it is obvious that the connecting means need not extend entirely across 35 the width of the shoe but may be subdivided into a plurality of connecting members 9, 9 which 40 interconnect the rear sole member 10 with intermediate section 11 and forward section 12 of the sole 13.

In Figure 4 the sole members 2 and 3 are provided with undercut slots 14, 15 into which a connecting member 16 may be introduced by sliding in the enlarged ends 17 and 18 thereof into the slot portions 14 and 15 from the side of sole members 2 and 3. If the portions of the connecting means and/or the interior of the slots have 50 been coated with cement or proper adhesive and then when the connecting means has been slid into place the same is allowed to dry thoroughly, said connecting means will permanently interconnect the sole sections in resilient manner allowing flexure of the sole as a whole by the

change of position occurring in the member 3 with respect to sole section 2. Said connecting means may well be of leather, synthetic or natural rubber or flexible plastic at will.

A slightly similar construction is shown in Figure 5, where the sole sections 2 and 3 have undercut slots 19 and 20 in which are seated the unsymmetrical ends 21, 22 of a flexible connecting member 23, the net result being the same as in the construction of Figure 4. In Figure 6 the connecting member 24 has rectangular anchoring ends 25, 26 seated in the sole sections 2 and 3 which may also be inserted and secured as mentioned with reference to Figures 4 and 5. In passing it might be stated that two or more connecting means may be used in spaced relation above each other instead of using merely one or a series in the same plane. This is shown in Figure 7 having the upper connecting means 27 and the lower connecting means 28 preferably one being of rubber or the like and the other of steel, beryllium copper or even rubber or plastic material, both connecting means being parallel and anchored in proper slots 29, 30 in the sole sections. In this case one connecting means will flex, while the other actually tends to stretch.

In Figure 8, the connecting means consists of a substantially flat steel spring 31 interconnecting sections 2 and 3 and with its ends extending into both sections, the two sections having clearances cut away at their inner portions 32, 33 to allow more general flexure of the spring so as to lengthen its radius of bending. The rivets, nails or screws 8, 8 pass vertically through the sole sections and the spring, but said spring is provided with extra large apertures 34, 35 which leave a margin of free space around said rivets or nails, etc., and thus allow a more ready and free flexure of the spring. Due to the resiliency of the spring it is of course evident that the same will tend to return the forward section of the sole into normal alignment when pressure is removed from the same, and it is relieved from direct contact with the floor or pavement, and the sole will therefore act more nearly like an ordinary leather sole and tend to keep the shoe straight. The connecting means need not constitute a single member as already intimated in connection with Figure 2 and Figure 7, but may consist in contrast with Figure 8 of a plurality of spaced arcuate steel springs 36 individually secured to the underside of arched slots 38, 39 in sole sections 2', 3' by means of staples 40, 40 or any other means known in the art. In order to secure the ends of the springs and thereby assist in holding them in place a pair of cleats 41 and 42 are secured in the arched slot or groove portions 38, 39 by means of cement, screws or nails to the sole sec-

tions 2', 3' so as to allow the ends of said springs to take against the upper portions of said cleats. The shape of these springs and their location will tend to arrest more or less strongly flexure of the sole by bending of said springs, as such bending will occur by partial straightening of the springs and the arcuate surfaces of the slot portions will also tend to militate against very sharp or too ready flexure not to mention that the very number of springs used will also determine the amount of flexure for a given weight or pressure applied to the sole.

When the connecting means consists of rubber or some other impervious material and extends the full width of the sole, it is quite obvious that the sole is rendered waterproof as well as flexible.

It is quite clear that the invention is not limited to the particular embodiments shown, for the latter are merely presented by way of a few non-limiting examples, and other modifications and constructions conforming to the principles of the invention may be resorted to within the scope of the appended claims.

Having now fully described our invention, we claim:

1. A sectional sole for footwear made of normally stiff or inflexible material divided transversely into two or more sole sections, and connecting means of flexible material secured to and interconnecting said sole sections so as to retain them in assembled relation and allow one section to alter position angularly with respect the next adjacent section by bending or flexure of the connecting means between them, said connecting means including at least one bent leaf spring occupying open recess portions forming an undercut gap between the same retaining means rigidly disposed upon said sections abutting the ends of said spring, and means securing portions of said

40 spring in the gap to both sections.

2. A sectional sole for footwear made of normally stiff or inflexible material divided transversely into two or more sole sections, and connecting means of flexible material secured to and interconnecting said sole sections so as to retain them in assembled relation and allow one section to alter position angularly with respect the next adjacent section by bending or flexure of the connecting means between them, said connecting means including at least one arcuate spring arched against arcuate portions of two adjacent sections in the gap between the same, means upon said sections disposed in said gap abutting the ends of said spring, and means securing portions of said spring in the gap to both sections.
